US00D845253S

(12) **United States Design Patent** (10) **Patent No.:** **US D845,253 S**
Cools (45) **Date of Patent:** **** Apr. 9, 2019**

(54) **CASING FOR EQUIPMENT FOR CONTROL OF ELECTRIC POWER**

(71) Applicant: **ATLAS COPCO AIRPOWER, NV**, Wilrijk (BE)

(72) Inventor: **Pieter Michel Mena Cools**, Wilrijk (BE)

(73) Assignee: **ATLAS COPCO AIRPOWER, NAAMLOZE VENNOOTSCHAP**, Wilrijk (BE)

(**) Term: **14 Years**

(21) Appl. No.: **29/512,702**

(22) Filed: **Dec. 22, 2014**

(30) **Foreign Application Priority Data**

Jul. 14, 2014 (EP) 002502278-0001

(51) **LOC (11) Cl.** **13-03**

(52) **U.S. Cl.**

USPC **D13/162**

(58) **Field of Classification Search**

USPC D13/110, 122-128, 133, 147, 158-160, D13/162, 168, 174, 184, 199

(57) **CLAIM**

The ornamental design for the casing for equipment for control of electric power, as shown and described.

DESCRIPTION

FIG. 1 is a perspective view of the Invention.

FIG. 2 is a rear view of the Invention.

FIG. 3 is a top view of the Invention.

FIG. 4 is a left side view of the Invention.

FIG. 5 is a bottom view of the Invention.

FIG. 6 is a right side view of the Invention; and,

FIG. 7 is a front side view of the Invention.

The broken lines illustrate subject matter that form no part of the claimed design.

1 Claim, 7 Drawing Sheets
